UNITED STATES PATENT OFFICE.

JOSEPH D. HUSBANDS, JR., OF ST. LOUIS, MISSOURI.

IMPROVEMENT IN GEARINGS FOR STONE-SAWING MACHINES.

Specification forming part of Letters Patent No. 148,066, dated March 3, 1874; application filed November 18, 1873.

To all whom it may concern:

Be it known that I, JOSEPH D. HUSBANDS, Jr., of St. Louis, Missouri, have invented an Improved Machine for Sawing Stone, of which the following is a specification:

The nature of this invention consists in the combination of parts, to operate as will now more fully appear.

Of the drawing, Figure 1 is a top plan; Fig. 2, a side elevation; Fig. 3, a modified screw-connection, instead of sliding table.

A is the frame of the machine. a' are standards on the frame, in the journal-bearings of which the respective shafts B B' turn. I provide each of the shafts B B' with a cone-shaped pulley or wheel, b b'. The arrangement of the cones b b' with relation to each other is, however, in the vice-versa position shown in Figs. 1, 2. The power source connects with the fixed belting-wheel C; C' being the loose belting-wheel, to which the change can be made when the machine is not to be operated.

In order to communicate the revolution of the cone b to the cone b' on the opposite shaft B', I provide the intermediate friction-pulley c. The friction-pulley c has its shaft properly supported to turn in journal-standards c¹ c². The standards c¹ c² are secured to the top of a slide-table, D. (See Figs. 1, 2.) The slide-table D operates on the frame A, being guided in its sliding action through guide-plates d d¹, Fig. 1. At bottom the table D is provided with a rack, d², in which meshes a gear-wheel, E, Fig. 2, which is on the transverse shaft e, which is operated by hand-crank e'. By turning the hand-crank e', a forward-and-backward motion is imparted to slide-table D. The saw or cutter attach-

ment is keyed to end of the shaft B'. As the friction-wheel c imparts the revolution of the cone b to that of b', it will further be noticed that, in causing the slide-table D to move forward and backward, the said friction-wheel is caused to act in combination with said respective cones, to achieve the required increased or diminished speed. By way of a modification, a running screw, F, can be provided. (See Fig. 3.) The standards c¹ c², carrying the friction-wheel c, are fitted to slide upon the face or top of table D, having flanged guides f f¹, said table, in this case, being made stationary. A running slot in table D (see Fig. 3) permits the standards c¹ c² to extend below the table, and so that through said standards the screw F is fitted to operate. At the end of screw F, by means of bevel-wheels f² f³ and hand-crank, the said screw is made to revolve and impart to the standards c¹ c², with friction-wheel c, the required slide or back-and-forward motion.

As apparent, the combination of parts aforesaid is applicable to all machines in which the speed is to be varied at will, or requiring an increased or diminished motion, without incurring any undue jar or irregular action or loss of power.

What I claim is—

The table D, operated by either rack and bar d² or screw F, in combination with friction-pulley c and cone-pulleys b b', substantially as described.

In testimony of said invention I have hereunto set my hand in presence of witnesses.

JOSEPH D. HUSBANDS, JR.
